BOOK REPAIRING

Filed June 4, 1928

UNITED STATES PATENT OFFICE

JAMES W. WARD, OF PITTSBURGH, PENNSYLVANIA

BOOK REPAIRING

Application filed June 4, 1928. Serial No. 282,785.

Books containing public records, such as transfers of real property, are subjected to constant use, and, as a result of the frequent turning of the leaves, the latter eventually break near the back or binding edge, and the unbound edges become frayed or torn so that patching with transparent gummed tape is resorted to to prevent complete destruction. My invention provides a method and means whereby the broken leaves may be repaired and rebound in a substantial but inexpensive manner, the strength and flexibility of the leaves renewed, and the books rendered fit for use without further deterioration through a long period of time. The invention is illustrated in the accompanying drawing and will be hereinafter fully set forth and particularly defined.

In the drawing:

Figure 1 is a sectional view showing a leaf and a binder strip prepared to be united;

Figure 2 is a similar view showing the parts joined;

Figure 3 is a similar view showing the repaired leaves as bound into a book;

Figure 4 is a similar view showing the leaves repaired and rebound in groups;

Figure 5 is a plan view of a leaf all the edges of which have been repaired;

Figure 6 is a view showing a further adaptation of the invention;

Figure 7 is a plan view and Fig. 8 an edge view of two leaves repaired and joined in another application of the invention;

Figure 9 is an edge view showing the repaired leaves of Figs. 7 and 8 folded into book form.

In the practice of the present invention, the book cover is, of course, removed. The fold of each signature is then cut off sufficiently to remove all paper touched by the old glue and produce substantial evenness in the frail worn portion of the leaves. With the book lying on its side, each leaf, as 1, is removed and its binding edge is skived, as at 2, either by hand or in a skiving machine, the skived leaves being piled flat so that the regular order or succession of the leaves will be maintained at all times. Bind-

er strips 3 are provided each having one side edge skived, as at 4, to mate with the skived edge of a leaf. Paste, glue or other adhesive is applied to the skived edges of the leaves and binder strips and a binder strip is imposed on each leaf, so that the skived edges will meet and form a joint extending diagonally across the plane of the leaf, as shown at 5. The leaves and attached binder strips are then placed in a press and left therein until the adhesive is thoroughly dry. Upon removal from the press, the repaired leaves will be in condition for rebinding, and the joints will be aligned, substantially as shown in Figure 3. It will be understood, however, that, prior to binding, the leaves are arranged so that their free edges will be even and the joints, consequently, will not always assume the exact regular relation shown. After the free edges of the leaves have been made even, the edges of the binder strips are trimmed evenly and the repaired sheets may be permanently bound or secured in a binder of the loose-leaf type.

Under some conditions, the leaves may be skived in groups, as 6, and the binder strips also skived in groups, 7, thereby expediting the work as a plurality of leaves or strips may be passed through the skiving machine at one operation. The joints 8 will extend through a greater portion of the thickness of the book with a corresponding increase in the strength and flexibility of the leaves.

It is to be understood that the binder strips are of new paper preferably a little thinner than the old paper in the leaves so as to permit an easy roll without forcing the bend into the old paper, and the skiving eliminates swells from the repaired sheets, the binding being applied to the new binder strips so that the old paper is relieved of all folding strain. The joint obtained by the described method is very strong, the old and the new paper being practically welded into a single continuous sheet. The text on the pages is not obscured, as no pasteur strips which are apt to extend over onto the text are employed. There is no definite breaking point in the repaired sheet whereas re-

bound books which have cambric or other material at the binding contain a definite breaking point which is found along the edge of such material.

5 Should a free edge of a leaf be badly worn, it may be repaired according to my described method, and in Figure 5 I have shown a leaf 9 all the edges have been so repaired. The binding repair strip 3 is the same as that 10 previously described. All the edges of the leaf are skived and facing repair strips 10, 11, and 12 are provided and each skived along a side edge to mate with one skived edge of the leaf. Some of the strips are 15 also skived at their ends or at an end to form a lap joint with a meeting strip, as indicated at 13 and 14, and the location of these end skives may be determined in any convenient manner as by measurement or a 20 preliminary test setting. The skived edges are then coated with adhesive, fitted together, and dried under pressure as before described. The free edge strips will preferably be narrower than the binder strips but 25 will have the same thickness as the old paper.

It may, sometimes, be found necessary or desirable to repair all the leaves of the book in which event the form of the invention illustrated in Fig. 6 may be employed. In 30 this arrangement, the leaf is skived on all four edges, as in Fig. 5, and a signature consisting of four sheets of new paper of the same thickness as the old paper is provided. Each sheet, as 15, is divided into 35 two leaves by a medial fold, as indicated at 16, and in each leaf is cut a window 17, all four edges of the window being skived as indicated at 18. Each windowed repair sheet is numbered as at 19, according to the 40 old sheet it is to receive, adhesive applied to the edges of the windows and of the old sheets, the old sheets fitted to the windows, and the whole placed in the drying press as in the previously described methods. When 45 thoroughly dried, the repaired sheets may be bound in any desired manner, by sewing through the fold or by whipstitching or by loose-leaf binding, and if they are to be made up loose-leaf or whipstitched, the 50 sheets will be cut through at the folding point and a little more width allowed on the binding edge. The sheets will, of course, be assembled with due regard to paging in the usual manner, the first sheet, for instance, 55 carrying pages 1, 2, 15 and 16, the next upper sheet 3, 4, 13 and 14, the third sheet 5, 6, 11 and 12, and the top or innermost sheet of the signature 7, 8, 9 and 10. One leaf is shown fitted in the window provided therefor at 20.

In the form of the invention shown in Figs. 7, 8 and 9, two leaves 21, 22, of a signature, say, pages 2 and 15, have their binding edges skived, as at 23, in the manner 60 previously described, the skives being rela-

tively reversed. A binding strip 24 is provided having the same length as the leaves 21 and 22 and its side edges are skived to mate with the skived edges of the leaves, as clearly shown in Fig. 7. This binding strip 70 is then disposed between the leaves, as shown in Figs. 7 and 8, and secured thereto by applying adhesive and drying under pressure, and, after drying, the leaves and strip are assembled in a signature and folded on 75 the medial line of the strip, as will be understood on reference to Fig. 9. The assembled leaves may be sewed through the folds of the binding strips and bound into a book in any known or approved manner. 80

Having fully described my invention what I claim as new and desire to secure by Letters-Patent, is:—

1. A method of repairing books which includes separating the leaves from the old 85 binding, uniting a binder strip to each leaf at an edge thereof, the joining edges of the leaf and the strip being skived whereby to form a joint passing through and diagonally between the opposite surfaces of the leaf, 90 the edge of the binder strip parallel with the joint being free to be secured in the book cover.

2. A method of repairing books which includes separating the leaves from the old 95 bindings, skiving the leaves along the binding edges thereof, skiving one side edge of each of a plurality of binder strips, imposing a binder strip upon each leaf with the skived edges in contact and coated with adhesive, drying the adhesive under pressure, and binding the strips. 100

3. A book leaf having a repair strip attached to its edge, the meeting edges of the strip and the leaf overlapping and forming 105 a joint passing through and obliquely between the opposite surfaces of the leaf.

4. A book leaf consisting of an old leaf having its edges skived, and a repair member having edges skived to lap the edges of the leaf and adhering thereto and having an unskived edge to be secured in a book 110 cover.

5. A method of repairing books which consists in separating the leaves from the old binding, skiving the edges of the leaves, providing a frame for each leaf, skiving the inner edges of the frame to mate with the skived edges of the leaf, applying adhesive 115 to the skived edges, imposing skived edges of the frame on skived edges of the leaf, drying the adhesive under pressure, and securing an unskived edge of the frame in the book cover. 120

6. The method of repairing books which consists in separating the leaves from the old binding, skiving the binding edges of the leaves, laying two leaves side by side in 125 spaced relation with skived edges opposed, 130

inserting a binder strip having skived edges between the skived edges of the two leaves with the skived edges of the strip imposed on the skived edges of the leaves, and uniting the binder strip to the leaves.

5 In testimony whereof, I have signed this specification.

JAMES W. WARD.
